DESIGN FOR A SMOKER'S PIPE

Forest F. Flint, Detroit, Mich., assignor to
Leo D. Gentle

Application April 22, 1947, Serial No. 138,531

Term of patent 7 years

(Cl. D85—8)

To all whom it may concern:

Be it known that I, Forest F. Flint, a citizen of the United States, residing in Detroit, in the county of Wayne and State of Michigan, have invented a new, original, and ornamental Design for a Smoker's Pipe, of which the following is a specification, reference being had to the accompanying drawing, forming a part thereof, wherein:

Fig. 1 is a top plan view of a smoker's pipe, showing my new design;

Fig. 2 is a side elevational view of the pipe shown in Fig. 1;

Fig. 3 is an end elevational view of the pipe shown in Fig. 2 taken looking from the left-hand end thereon; and

Fig. 4 is an end elevational view of the pipe shown in Fig. 2 taken looking from the right-hand end thereon.

I claim:

The ornamental design for a smoker's pipe, as shown.
